COMBINED BOTTLE AND OVERCAP

Alain Carré, Paris, France, assignor to
Waterman S.A., Paris, France

Filed Apr. 29, 1975, Ser. No. 572,914

Claims priority, application France Nov. 4, 1974

Term of patent 14 years

Int. Cl. D9—01

U.S. Cl. D9—59

FIG. 1

FIG. 4

FIG. 2

FIG. 5

FIG. 3

FIG. 6

FIG. 1 is a side elevational view of a combined bottle and overcap showing my new design, the opposite side being the same in appearance;

FIG. 2 is an end elevational view;

FIG. 3 is a top plan view;

FIG. 4 is a side elevational view with the overcap removed, the opposite side being a mirror image thereof;

FIG. 5 is an end elevational view thereof; and

FIG. 6 is a top plan view thereof.

I claim:

The ornamental design for a combined bottle and overcap, as shown and described.
